UNITED STATES PATENT OFFICE.

WILLIAM B. FENN, OF WASHINGTON, PENNSYLVANIA.

JAR-CLOSURE.

SPECIFICATION forming part of Letters Patent No. 758,515, dated April 26, 1904.

Application filed June 1, 1903. Serial No. 159,398. (No model.)

To all whom it may concern:

Be it known that I, WILLIAM B. FENN, a citizen of the United States, residing at Washington, in the State of Pennsylvania, have invented 5 certain new and useful Improvements in Jar-Closures, of which the following is a specification.

My invention relates to means for closing and sealing jars, bottles and other like vessels, 10 and particularly to the kind of jars used for preserving fruits etc., requiring an easily removable seal. Its objects are to provide a closure which avoids any contact of metallic parts with the contents of the jar, to provide for 15 the use of a glass or non-metallic cap, to provide means for inducing differential pressure upon the packing or seal and a closure easy of manipulation and accurate in its working, and without liability of getting stuck in place.

20 In order to gain the above objects, as well as to make the jar cap conveniently in a press mold, and to gain other advantages, I use the structure as illustrated in preferred form in the accompanying drawings, wherein,—

25 Figure 1 is a view of the metallic attaching strap; Figure 2 is a cross section of the cap, and Figure 3 of the upper part of the neck and jar, as designed to use my invention.

Figure 4 is a vertical sectional view through 30 the cap and strap as joined together on the jar, showing the neck of the latter in side elevation, with the form of the differential threads I prefer. Figure 5 shows a blank for the metallic strap.

35 In carrying out my invention I provide upon the neck of the jar *a* a pair of oppositely disposed slanting threads *c*, which are interrupted by spaces *d* at two opposite points. The cap of the jar is provided with an annular 40 groove and with a depressed central portion to fit inside the mouth of the jar. To retain the cap I use the metallic strap *g*, which is provided also with a depressed portion to fit inside the depression of the cap, and upon its 45 side leg has two inwardly projecting spurs *k* and *h*. The legs are sprung over the edge of the cap and the spurs *k* thus hold the cap and metallic strap together. The inwardly projecting studs *h* are to take under the threads

c, being introduced through open spaces *d*, 50 and thus upon giving the cap or the strap a sidewise turn they draw the cap down upon the packing *m* as shown in Figure 4.

By this means I avoid any contact of metal with the contents of the jar and need to use 55 only the very small packing ring *m*, and the cap itself may be made entirely of glass. The device is tightened in place by the maximum of a half turn of the strap or the cap of the jar, and is very conveniently released from place, 60 all as will be evident from the drawing. The cap and the retaining strap are securely attached together and do not come apart when the cap is removed, so that for all practical purposes of handling they are as one piece, 65 while the strap is of very cheap and convenient form and the cap may be easily made by pressing in molds. The simplicity and ease of operation of the device will readily occur to those familiar with its use.

70 While the form of the metallic strap is not an essential part of the invention, I prefer to make it of sheet steel, and it may conveniently be made by cutting from a blank as shown in Figure 5, the lugs being bent in at right angles 75 to the face of the strap, as will be understood.

Having thus described my invention, what I claim as new, and desire to secure by Letters Patent, is the following:

1. In a jar closure the combination with the 80 neck having threads thereon, of a glass cap having a depressed center and a groove for carrying packing, and a metal strap provided with a depressed portion engaging the top of the cap, inturned spurs to hold the strap on 85 the cap, and depending studs arranged to engage the threads of the neck.

2. In a jar closure the combination of a neck provided with oppositely disposed partial threads with an open space between their ends, 90 of a glass cap provided with a central depressed portion, an annular groove for containing packing, and an undercut outer rim, a metallic strap engaging the depressed top of the cap, having spurs sprung over and engaging the rim 95 of the cap, and inturned lugs to engage the threads on the neck; substantially as described.

3. In a jar closure the combination with a

threaded jar neck and a cap having a depressed central portion and an overhung rim, of a strap comprising a sheet metal bar provided on each end with upwardly hooked spurs to engage the cap and with a pair of lugs to engage the threads on the jar neck, and a depressed center to engage the cap.

In testimony whereof I have hereunder signed my name in the presence of the two subscribed witnesses.

WILLIAM B. FENN.
